UNITED STATES PATENT OFFICE.

CHARLES B. WINDER, OF COLUMBUS, OHIO.

CAMP EQUIPMENT.

1,260,845.

Specification of Letters Patent. Patented Mar. 26, 1918.

Application filed June 28, 1916. Serial No. 106,498.

To all whom it may concern:

Be it known that I, CHARLES B. WINDER, a citizen of the United States, residing at Columbus, in the county of Franklin and 5 State of Ohio, have invented certain new and useful Improvements in Camp Equipment, of which the following is a specification.

This invention relates to improvements in 10 camp equipment which is especially adapted for use by soldiers on the march or in camp, by boy scouts, or by family camping parties; and has for its primary object to provide an equipment which may be transposed into a 15 combined tent and cot or into several separate garments.

It is also one of the principal objects of 20 this invention to make a device of this character which is light in weight and is collapsible, so that it may be folded into small compass to be carried on the back.

These and other objects are attained by the means illustrated in the accompanying drawings, in which:—

25 Figure 1 is a perspective view of the invention used as a combined cot and shelter in its simplest form.

Fig. 2 is a detail perspective view of one of the end supports.

30 Fig. 3 is a detail view partly in longitudinal section through one of the end supporting bars.

Fig. 4 is a perspective view of a detachable lining or blanket used on the cot.

35 Fig. 5 is a fragmentary sectional view through a portion of the blanket.

Fig. 6 is a plan view of the cot bottom detached from its supports.

Fig. 7 is a transverse sectional view on 40 the line VII—VII of Fig. 6.

Fig. 8 is a detail plan view of the supporting bar at the foot end of the device, the end wall 17^a being turned outwardly, and the legs and the end-wall support being 45 ing shown folded.

Fig. 9 is a detail perspective view of the upper end of one of the end-walls and its co-operating support.

Fig. 10 is a perspective view of the device 50 used as a covered tent.

Figs. 11 and 12 are diagrammatic end views of the device showing different uses.

Fig. 13 is a view showing the cot bottom used as a coat, and

55 Fig. 14 is a view showing the device folded in a position to be strapped upon the back.

Similar reference numerals in all of the figures of the drawings designate like parts.

Referring to Fig. 1, the device is shown in its simplest form, and comprises foot and 60 head supports 15 and 16, respectively, and a cot body 17 suspended between said supports.

Each of said supports 15 and 16 embodies a horizontal supporting bar 18, provided with a series of hooks 19 and with 65

a pair of legs 20 and 21, which latter are pivoted together at 22, while leg 20 has its upper ends pivoted to said bar 18 at 23.

The upper end of bar 21 is adapted to engage in one of several recesses 24 formed on the under side of bar 18. Thus, when the legs are

in open position they form a crossed support for their bar 18, and by withdrawing the upper end of the leg 21 from the recess 24 in the bar the legs may be folded to lie substantially in parallel relation to said bar.

Each supporting bar 18 has pivoted thereto at 25 a foldable end-wall support 26, preferably formed in two sections pivoted together at 27, so that one section may be folded alongside of the other, and both sections

may then be folded in parallel relation to the bar 18. The pivot 27 is preferably a thumb screw, which can be tightened to retain the sections in vertical alinement to support the 50

collapsible end-walls 17^a in an upright position. Said end-walls are preferably tri-

angular in shape and have their lower edges secured to the supporting bars 18, and at their apices are provided with eyes 28 which 55

engage over the studs 29 secured in the upper ends of the end-wall supports 26. The

head end-wall 17^a preferably is provided with a gauze covered opening 30, over which

is hinged an adjustable flexible shutter or 60

cover 31, adapted to swing upwardly from its lower edge, said cover being retained ex-

tended by a rigid central rod 32, and being 65

capable of operation up and down from the

inside of the wall through lifting cord 33 70

and retaining cords 34, which pass through

apertures or eyes formed in the head end-

wall 17^a.

The cot proper 17 preferably is formed with a relatively heavy canvas bottom 35 105

and a relatively light top 36, said bottom be-

ing provided across its ends with a series

of eyelets 37, which are adapted to engage

over the hooks 19 of the supporting bars 18,

said bottom being held suspended in a taut 110

position by tension means consisting of

chains 37^a secured to the end bars 18 and

extending outwardly therefrom and with their other ends secured to suitable stakes 38 driven into the ground in the usual manner, the tension of these chains being adjusted by the sliding blocks 39. It has been found by experiment that a single stake will loosen and pull out of the ground under the load imposed upon the cot, and therefore I have provided additional stakes 40, which 10 are connected in tandem with stakes 38 by cables or chains 41.

Both the foot and head end-walls 17^a are supported against inward movement by the guy cords 42, the same being provided at 15 one end with loops to engage over the studs 29, and at their other ends with snap-hooks 43 adapted to engage with the tension chains 37^a.

The top section 36 of the cot proper, as 20 before stated, preferably is formed of relatively light material, and is cut considerably wider than the bottom section 35, so that when its edges are secured to the edges of the bottom section 35 there is sufficient fullness to form a sleeping bag. The lower end or foot portion of the bag, formed by said top and bottom sections 35 and 36 is closed, while its upper end or head portion is open at one side, the coöperating edges of said 25 30 open portion being provided with suitable fastening means, while intermediate its ends, or at the junction of the foot and head portions, is provided a slot 44 and a collar 45, for a purpose hereinafter to be described. 35 Transversely opposite said slot 44 and collar 45 are secured garment sleeves 46. The head portion of the top section 36 is formed considerably wider than the foot portion and extends beyond the edge of the bottom section 35, so that the free edge of the section 36 can be secured by suitable fasteners to and around the free edges of the head end-wall 17^a.

It has been found desirable to provide a 45 blanket 47 for the sleeping bag formed by the sections 35 and 36, and, as shown clearly in Fig. 4 of the drawings, the same is constructed similarly to said sleeping bag, and is of a size to fit snugly therein. This blanket 50 preferably is constructed of superposed layers of light weight fabric and paper.

Connected at each end to the hooks 19, and disposed beneath the cot proper, is a supporting webbing which is formed of 55 longitudinal strips 48 connected together intermediate their ends by the straps 49. These straps 49 are provided with buckles 50, which are adapted to be engaged by the opposite free ends of said straps when 60 wrapped around the device in a folded position. Also suspended beneath the cot proper and said supporting webbing is a protector sheet 51, which also is provided with eyelets at its ends to engage the hooks 65 19 of the supporting bars 18, and preferably

is constructed to be drawn or puckered at or near the center of its side edges to draw said edges taut and form an air chamber between said protector sheet and the bottom of the cot. A portion of the upper edge of the section 36 is shown in Fig. 1 attached to one inclined side of the head end-wall 17^a, the rest of it being thrown backward, but adapted to be fastened to a flap 36^a permanently fastened to the bottom section 35 70 and provided with fastening means to engage the fastening means on the side of the section 36. From this construction it is obvious that a person may enter beneath the open portion of the top section 36 and may 80 lie therein with his head exposed. Or he may unite the free edge of the section 36 with flap 36^a, thus entirely covering himself, and may secure ventilation through the aperture 30, while in cold weather he may insert the blanket 47 before entering the bag. The foot end-wall 17^a is not necessary when used as before described, it being shown in this figure simply for illustration.

When it is desired to utilize the device as 90 a lounging cot, and not a sleeping bag, it is obvious that the cot proper may be removed from the hooks 19 and replaced in a reversed position with the canvas side 35 uppermost, and in stormy weather the article may be 95 detached from its supports and utilized as a storm coat, as shown in Fig. 13 of the drawings. When used as a coat, as shown in this figure, the slot 44 serves as an aperture for the neck, and the closed foot portion hangs 100 in a double thickness upon the back. It is understood that the material is water-proof.

In Fig. 10, the device is shown as a combined tent and sleeping bag, and when used as such a sheet 52 is provided which is detachably secured at its ends to the edges of the end-walls 17^a, forming a shelter cover in the shape of a peaked roof over the sleeping bag, as clearly shown in Fig. 7 of the drawings. The sheet 52 is provided with an 110 aperture 53 and a collar 54 which serve to form a poncho of the sheet when desired.

In Fig. 11 is shown another adaptation of the device, wherein one side portion of the sheet 52 is shown horizontally extended from the apex of the tent and furnished at its corners with suitable props 53. Also in this figure sheet 51 has been detached from the cot, and is supported as an extension of the sheet 52, said formation providing a combined sleeping and shelter tent. In Fig. 12 is shown two units or tents with their sheets 52 projecting toward each other and united at their free edges, said formation providing a shelter tent with a cot on each side. 115 120 125

The blanket 47, being constructed similarly to the sleeping bag also may be worn as a bath robe or other like garment.

The complete device is collapsed and folded as follows:—

The tension is first taken from the chains 37^a by slipping the blocks 39 downwardly toward the stakes 38, and the upper ends of the legs 21 are disengaged from the recesses 24 in the bars 18. The whole device will then lie flat upon the ground, and the legs 20 and 21 may be folded in close relation to the bars 18, as are also the vertical supports 26 for the end-walls 17^a. The end-walls 17^a are laid flat upon the top of the cot, and the stakes are then withdrawn from the ground and placed alongside the bars 18, and the whole device, excepting the shelter sheet 52, the reinforcing webbing 48 and the protector sheet 51, is then given a series of folds to form an elongated package, which is as long as the folded legs 20 and 21. The shelter sheet 52 then is folded to a corresponding length, and is wrapped around said package, and the protector sheet 51 then is placed upon the ground, and the package folded therein. This completes the package, and to retain the same in this position the reinforcing webbing is used as a binder and also to attach the same to the body of a person who wishes to carry it. The package is placed upon the two longitudinal strips 48 of reinforcing webbing intermediate their ends, and the straps 49 are carried transversely around the package and buckled tightly in position. This leaves the ends of the longitudinal strips 48 free, and two of said ends may be carried over the shoulders of the wearer and beneath the arm pits and secured by their end hooks to one of the straps 49, as shown clearly in Fig. 14. The other free ends of said strips 48 are then brought around the body and passed upwardly across each other on the front of the body and attached to the first-mentioned ends by suitable fasteners. As thus supported the package lies in the middle of the back, and the person carrying the same has free use of both of his arms. In fact, it forms a package similar to a knapsack.

It will be observed that the reinforcing webbing 48 and 49 when secured in position beneath the cot proper will maintain the tension between the end supports when the cot proper is removed, so that when it is desired to use the cot proper as a garment or water-proof coat it may be detached from the end supports without danger of a collapse of the whole device.

Having thus described my invention, what I claim as new and desire to secure by Letters Patent, is:—

1. In a camp equipment, a pair of end supports, a cot body detachably suspended from said end supports and formed of bottom and top sections which are united to provide a permanently closed foot portion and a head portion adapted to be opened, said top section being provided with a slot intermediate

its ends to serve as a neck aperture when worn as a coat, and tension means for retaining said end supports in position to suspend said cot body.

2. In a camp equipment, a pair of end supports, a cot body detachably suspended from said end supports and formed of bottom and top sections which are united to provide a permanently closed foot portion and a head portion adapted to be opened, said top section being provided with a slot intermediate its ends to serve as a neck aperture when worn as a coat and with a pair of sleeves secured at the sides of said sections and in transverse alignment with said slot, and tension means for retaining said end supports in position to suspend said cot body.

3. In a camp equipment, a pair of end supports each comprising crossed legs pivoted to each other and a horizontal cross bar detachably supported thereon and provided with attaching means, a cot body detachably secured to said cross bars through said attaching means, and tension means engaging said end supports for retaining the same in position with said cot body stretched therebetween.

4. In a camp equipment, a pair of end supports each comprising crossed legs pivoted to each other and a horizontal cross bar detachably supported thereon and provided with attaching means, foldable end wall supports centrally pivoted to said cross bars, a cot body detachably secured to said cross bars through said attaching means, collapsible end walls secured to said cross bars and retained in position by said foldable end wall supports, and tension means engaging said end supports for retaining the same in position with said cot body stretched therebetween.

5. In a camp equipment, a pair of folding end supports, a collapsible head end-wall secured to one of said supports, a cot body detachably secured to said end supports and formed of bottom and top sections which are united to provide a head portion adapted to be opened and whose free edge is adapted to engage the free edges of said head end-wall, and tension means for retaining said end supports in position to suspend said cot body.

6. In a camp equipment, a pair of end supports, a cot body secured to said end supports, a protector sheet secured to said end supports beneath said cot body and spaced therefrom to form an air chamber, and tension means for retaining said end supports in position to suspend said cot body and protector sheet.

7. In a camp equipment, a pair of end supports, a cot body detachably secured to said end supports, a protector sheet detachably secured to said end supports beneath

said cot body and spaced therefrom to form an air chamber; and tension means for retaining said end supports in position to suspend said cot body and protector sheet.

- 5 8. In a camp equipment, a pair of end supports, a cot body detachably secured to said end supports, a reinforcing webbing also secured to said end supports beneath said cot body, and tension means for retaining said end supports in position to suspend said cot body, said webbing serving to maintain said end supports in position under said tension when said cot body is removed.
- 10 9. In a camp equipment, a pair of end

supports, a cot body detachably secured to 15 said end supports, a reinforcing webbing also detachably secured to said end supports beneath said cot body, and tension means for retaining said end supports in position to suspend said cot body, said webbing serving to 20 maintain said end supports in position under said tension when said cot body is removed, and serving when the parts are in folded position as a retaining means therefor.

In testimony whereof I hereunto set my hand this 17th day of June, 1916.

CHARLES B. WINDER.
